Des. 185,515
Patented June 16, 1959

185,515

BEVERAGE STIRRING STICK

Harold Silver and Howard Black, New York, N.Y.

Application March 12, 1957, Serial No. 45,235

Term of patent 14 years

(Cl. D44—29)

Figure 1 is a front elevational view of the beverage stirring stick showing our new design;

Figure 2 is a side elevational view thereof;

Figure 3 is an enlarged front elevational view with a portion broken away for convenience of illustration; and

Figure 4 is a side elevational of the beverage stirring stick as shown in Figure 3.

We claim:

The ornamental design for a beverage stirring stick, as shown.
